UNITED STATES PATENT OFFICE.

BERT G. DUNHAM, OF HAWTHORNE, NEW JERSEY, ASSIGNOR TO WESTERN ELECTRIC COMPANY, INCORPORATED, OF NEW YORK, N. Y., A CORPORATION OF NEW YORK.

PAY-STATION TELEPHONE SYSTEM.

Application filed August 1, 1923 Serial No. 655,028.

To all whom it may concern:

Be it known that I, BERT G. DUNHAM, a citizen of the United States of America, residing at Hawthorne, in the county of Passaic, State of New Jersey, United States of America, have invented certain new and useful Improvements in Pay-Station Telephone Systems, of which the following is a full, clear, concise, and exact description.

This invention relates to automatic telephone systems and more particularly to pay station automatic telephone systems.

In such systems means is usually provided to enable the calling subscribers to select an operator's position on special calls, such as toll calls.

The object of this invention is to provide a circuit arrangement which automatically functions upon the breaking down of the connection to dispose of the coin or coins deposited in the calling line coin box if the operator fails to dispose of them before the connection is released.

In accordance with this invention the operator is provided with means for impressing current upon the calling line selectively to actuate the coin box magnet, and additional means is provided associated with the trunk taken for use by the calling party which means is automatically actuated during the breaking down of the connection to apply current to the calling line to actuate said magnet to dispose of the deposited coin or coins in case the operator has failed to do so. In the present embodiment in such cases the coin is automatically refunded to the calling subscriber. This is the preferred arrangement owing to the relatively large number of calls made to the special positions and for which no charge is to be made.

Referring to the drawings,

Fig. 1 shows a calling line, a line switch and the coin control circuit; Fig. 2 shows a secondary line switch, a selector, and a called line; Fig. 3 shows a trunk leading from one of the levels of the selector to the operator's position, and Fig. 4 shows the equipment at said position for enabling the operator to select the trunk used by the calling subscriber and to control the disposition of the deposited coins thereover.

The invention will be most readily understood from a detailed description of the

operations involved in setting up a connection.

Upon the removal of the receiver at the calling substation, the relay 101 of the primary line switch PLS individual to the calling line is operated over the calling line circuit. In attracting its armature it closes a circuit including the pull down winding 102 of the line switch which causes the line switch to seize the preselected trunk by operating the set of springs in the well known manner, as shown and particularly described for example in Patent No. 1,304,369, to A. J. Ray of May 20, 1919. The calling line is now extended to the trunk circuit, whereupon relay L is operated as follows: free pole of battery, contact 104 of relay Y, conductor 105, contact 106 of relay S', conductor 107, contact 198 of relay N N, resistance 187, conductors 109, 110, the inner right armature and back contact of relay B, lower armature and back contact of relay A, ring conductor 165 including contacts 162, 163 of the line switch, the telephonic loop at the calling substation, tip conductor 164, including springs 166, 167 of the line switch, upper armature and back contact of relay A, left armature and back contact of relay B, retardation coil 188, relay L, outer left armature and back contact of relay N N to ground. Relay L closes a circuit for the cut-off winding 107 of the line switch to hold the line switch set before the circuit for the pull down winding 102 is opened as the line relay 101 releases. The circuit for the cut-off winding is as follows: ground, left armature and front contact of relay L, conductor 108, outer right armature and back contact of relay H H, conductor 199, contact 110 of relay N N, conductor 146, release or sleeve conductor 125, springs 112, 113 cut off winding 107, free pole of battery.

When the primary line switch PLS operated and closed springs 114, 115 the following circuit was closed to operate the secondary line switch SLS to seize an idle first selector, grounded spring 115, spring 114, secondary line switch holding conductor 116, outer left armature and back contact of relay H H, conductors 117, 202, pull down coil 203 of the secondary line switch, contact 204, conductor 205, slow relay 206, to

free pole of battery. The secondary line switch SLS in operating closes a locking circuit for itself, including its windings 207, 203 in series and contact 208, to grounded holding conductor 201.

5 Relay L, in attracting its left armature, operates slow to release relay N, which operates relay N N. Relay N N in attracting its outer left armature removes the shunt from about the high resistance 118 for a purpose which will shortly appear, and in attracting its inner left armature grounds the release conductor 125 over conductor 146 to hold up the primary switch PLS after relay L releases.

10 Relay N N in attracting its inner right armature substitutes relay RT for resistance 187 in the calling line circuit. Relay RT is thus connected to the ring side 165 of the 20 calling line.

15 Relay RT is marginal and will not operate in the line circuit due to the high resistance 118 and relay L. Resistance 118 is normally short circuited, its short circuit being removed when relay N N operates to increase the margin of operation of relay RT.

20 The circuit remains in this condition until the calling party inserts a coin in the coin box. The coin box may be of the type shown and described in Patent 1,043,219 of November 5, 1912, to O. F. Forsberg. As shown and described in detail in said patent the deposited coin causes the closure of contact 120 to ground the tip side of the line 164 and, since the receiver is now removed from its hook, this ground is also connected to the ring side of the line 165. The application of this ground closes a shunt about 25 relay L and the high resistance 118, whereupon the marginal relay RT operates over a circuit including the ring side of the line 165, the calling substation receiver hook, and the ground closed by contact 120 of the coin box.

30 Relay RT in operating, energizes relay S' over the following circuit: battery, armature and front contact of relay RT, conductor 121, relay S', conductors 122, 123, outer left armature and front contact of relay N N to ground. In attracting its outermost left armature, relay S' connects conductor 116 to conductor 117 independently of the outer left armature and back contact of relay H H. In attracting its middle left armature, relay S' provides a direct path to ground through coil 188 from the tip side 164 of the line short circuiting relay L and resistance 118. Relay L releasing, 35 opens the circuit of relay N which is slow to release. In attracting its innermost left armature, relay S' connects the impulse relay R' to the ring side 165 of the line. In attracting its inner right armature it releases relay RT from the calling line circuit and locks itself to grounded battery at a

40 normal contact of relay Y and to the grounded sleeve or release conductor 124. This conductor was grounded when the secondary line switch seized the first selector in the well known manner. The locking circuit of relay S' is as follows: free pole of 70 battery, contact 104 of relay Y, conductor 105, inner right armature and front contact of relay S', relay S', conductor 122, grounded sleeve wire 124. In attracting its outer 75 right armature, it operates relay H H and slow relay H. The circuit for relay H H leads over conductor 176 and the outer right armature of relay B and conductor 189. Relay H then locks itself over conductors 80 174, 176, outer right armature and back contact of relay B, conductor 189 to battery at its own armature and front contact. Relay 85 H H being connected to conductor 189 is also held up by the armature of relay H. 86

90 Relay H H in attracting its inner right armature, connects grounded conductor 148 over conductor 147 to the release conductor 125, leading back to the primary line switch to maintain the cut off winding 107 thereof energized independently of the ground supplied at the inner left armature of relay N N, which relay releases when slow relay N releases, the circuit of relay N having been opened as relay L was short 95 circuited when relay S' operated. The grounded conductor 148 is however extended to the sleeve conductor 125 by relay H H before relay N, which is slow, releases.

99 The calling party now operates his sender 100 in accordance with the first digit of the wanted number, and on the return of the sender, to its normal position, the following circuit including the impulse relay R' is interrupted: free pole of battery, relay 103 R', conductor 126, inner left armature and front contact of relay S', conductors 127, 128, inner right armature and back contact of relay B, lower contacts of relay A, the ring side 165 of the line, the substation loop, 110 the tip side 164 of the line, the upper back contacts of relay A, left armature and back contact of relay B, retardation coil 188 to ground at the middle left armature of relay S'. The ground connected to the tip side 115 of the line at spring 120 does not interfere with this impulse circuit. Upon initial operation of relay R' before the sender was operated, it closed at its lower front contact a circuit for slow-to-operate relay D which 120 in operating extended the front contact of relay R' to energize relay D D which connected the incoming and outgoing ends of the tip and ring conductors together, these conductors including a pair of condensers 125 129, 130. Upon the first retraction of the armature of impulse relay R', due to the sender interrupting the line, relay D D instantly retracts its armatures, disconnecting the incoming tip and ring conductors 130

from the outgoing tip and ring conductors. Relay D is constructed and arranged so that it will not again attract its armature while the impulse relay armature is vibrating. 5 Relay D thus remains inert during this period to maintain the condensers disconnected from the outgoing ends of the tip and ring conductors to prevent interference with the character of the impulses, by the 10 discharge of the condensers.

Only parts of the switches S and C are shown, since these switches are well known. They may be of the type shown in Reissue Patent No. 13,901, issued April 13, 1915, to 15 F. Newforth, Jr.

Assuming that the selector S and preceding switches have been set and the calling line extended to the connector C, the impulse relay 210 (Fig. 2) of the connector C is 20 operated over the following circuit: free pole of battery, right winding of relay 210, normal contact of relay 211, conductor 233, ring conductor 212, multiple terminal 213 and brush 214 of the selector S, ring conductor 215, secondary line switch contact 216, ring conductor 132, (Fig. 1) contact 133 of relay J, conductor 134, upper armature and front contact of relay R', conductors 135 and 136, retardation coil 181, polarized relay P, tip conductor 139 including contact 140 of relay J, tip conductor 195, contact 226, tip conductor 227, brush 228, terminal 229 of selector S, tip conductor 230, conductor 231, outer normal contact of 35 relay 211, left winding of relay 210 to ground. Relay 210 at its front contact operates slow relay 240, which interposes a break in the circuit of release magnet 241 and grounds the sleeve wire 245 in the well 40 known manner.

The operations of setting the connector need not be described since they are well known and form no part of this invention. The impulse relay R', which is in circuit 45 with the sender, at its upper armature and front contact controls the circuit of the connector impulse relay 210.

When the connection has been built up to the called line, the response of the called 50 party operates relay 211 which reverses the flow of current in the tip and ring conductors leading back to the coin collect circuit. Relay P, which is polarized, thereupon operates, closing a circuit for relay C to prepare 55 a circuit including the coin collect source C C and the calling line. The circuit for relay C is as follows: free pole of battery, relay C and its normal upper contact, conductor 142, armature and contact of relay P, conductors 192, 157, 146 to the release conductor 125, which is grounded at the inner 60 right armature of relay H H. Relay C in attracting its armature 155 locks itself to conductor 146. Relay J is also energized 65 over the following circuit due to the opera-

tion of relay P; free pole of battery, resistance 184, relay J, conductor 150, armature of relay K, conductor 142, contact and armature of relay P, conductors 192, 157, 146, to ground over the path traced for relay C. 70 Relay J locks itself over its armature 152, conductors 151, 157, to grounded conductor 146, as previously traced. Relay J reverses the connections of the tip and ring conductors 195 and 132 with the tip and ring conductors 139, 134 for a purpose which will appear later. Relay C in operating, closes the following circuit for relay A: free pole of battery relay A, conductor 154, uppermost armature and front contact of relay 80 C, to the grounded sleeve conductor 124. Relay A extends the tip and ring conductors leading from the primary line switch to the tip and ring conductors 139, 134, cutting off the bridge containing the impulse 85 relay R' and retardation coil 188. Relay R' in releasing its upper armature removes the bridge containing the impedance coil 181 from across the talking conductors.

The subscribers may now converse. Talking current is fed from the connector to the calling line over the following circuit: free pole of battery, right winding of relay 210, outer armature and front contact of relay 211, conductors 231, 230, terminal 229, 95 brush 228, conductor 227, contact 226, conductor 195, contact 159, of relay J, conductors 134, 160, 161, lower armature and front contact of relay A contact springs 162, 163, conductor 165, through the substation talk-set, conductor 164, springs 166, 167, conductor 164, upper armature and front contact of relay A, conductor 168, relay P, conductors 139, 170, armature 169 and front contact of relay J, conductor 132, contact 216, 100 conductor 215, brush 214, terminal 213, conductors 212, 233, inner armature and front contact of relay 211, left winding of relay 210 to ground. Current is fed to the called line over the windings of relay 211. 105

When the calling party replaces his receiver, ground is removed from the sleeve conductor 245 by the release of slow relay 240, which causes the connector and selectors to restore. The removal of this ground 110 also releases relay S', which in releasing its outer left armature releases the secondary line switch SLS. Relay S' at its outer right armature and back contact also closes a circuit for relay Y as follows: free pole of battery, outer right armature and back contact of relay S', conductor 171, relay Y, contact 172 of said relay, conductor 173, inner left armature of relay H H, lower contact of the constantly operating interrupting 115 machine I to ground, when the lower contact is closed by the cam of the machine. Relay Y in operating, locks itself to grounded conductor 148 by closing its contact 177. 120

When the interrupting machine I next 125

closes its upper contact, an impulse of current is delivered to coin current applying relay B over the inner left armature and front contact of relay Y. This relay in attracting its armatures impresses positive current of preferably 110 volts from the collect source C C to the calling line to operate the polarized magnet PR in the coin box at the calling station to collect the coin. This circuit is as follows: free pole of source C C, conductor 178, lower armature and front contact of relay C, relay 190, conductor 179, left armature and front contact of relay B, upper armature and back contact of relay 15 A, springs 167, 166, tip conductor 164, contact 120, polarized magnet PR to ground. Relay A released when ground was removed from the sleeve conductor at the connector. The polarized magnet PR operates to collect 20 the coin as shown and described in said Forsberg patent. In operating, magnet PR locks itself to ground by closing contact 119 and then releases the coin, opening contact 120. Due to the closure of contact 119 the 25 magnet PR remains operated as long as the coin current is applied, as shown and described in detail in said Forsberg patent. In case the first impulse from the interrupting machine fails to cause the collection of 30 the coin, additional impulses are sent and the release of the primary line switch PLS is held up in the following manner: when the relay B operated, in attracting its outer right armature it opened the locking circuit 35 previously traced for slow relay H, but before the relay H can de-energize, a substitute circuit is closed by the armature of relay 190 which operates in the coin current circuit in series with the polarized magnet 40 PR. Relay H as pointed out holds up relay H H which at its inner right armature is maintaining ground on the sleeve conductor leading to the holding winding 107 of the primary line switch. Thus these two alter- 45 nate circuits maintain relay H operated until the ground at the substation is removed. As long as relay Y remains operated, lamp 180 lights before an attendant, who will 50 investigate in case the apparatus does not function properly.

Assuming, as in the normal case, that the polarized magnet PR functions properly, the second time the relay B operates from the interrupter I no ground will be present 55 at the substation and the relay 190 will fail to operate and the substitute circuit for relay H at the front contact of relay 190 will not be present when relay B opens the other circuit at its outer right armature and back 60 contact when it is next operated from the interrupter I. Relay H accordingly releases, releasing relay H H. Relay H H in retracting its inner right armature removes ground from the sleeve conductor 65 leading to the holding winding 207 of the

line switch SLS, resulting in the release of the same.

In case the called party has not responded, polarized relay P would not have shifted its armature and relay C would have remained inert. At its lower armature, this relay would have connected negative current from the 110 volt coin return source CR to the calling line to cause the polarized magnet PR to refund the coin, lock up to ground at 70 contact 196, and open contact 120. When the operating current ceases, magnet PR releases, opening contact 196 whereupon the primary line switch would release as described. 75

Certain lines called free lines are segregated upon connectors which do not reverse the current flow in the calling line when the called party responds. On such calls, battery is fed to the calling line over the impulse circuit previously traced, the relay R' being balanced by the retardation coil 188, the condensers 129, 130 separating the calling and called ends of the circuit. 80

The retardation coil 181 is provided in 90 these calls to prevent short circuiting the voice currents.

Upon disconnection in this class of calls, inasmuch as relay C is not operated, the coin is refunded as in the case of unsuccessful calls. 95

Resistance 182 is connected to ground at one end and to the condensers 129, 130 at the other end over normal contacts of relay D D. The other terminals of these condensers are connected over normal contacts of relay A to the armatures of relay B over which the relatively high potential coin current flows. This arrangement is for preventing the burning of the contacts of relay B when the high voltage coin current is cut off by the interrupter I releasing relay B. 100 105

The ground applied by the polarized magnet PR is connected to the tip side 164 of 110 the line and the ground through the relay 210 at the connector is also normally applied to the same side of the line. However, when the relay 211 is operated when the called party answers, battery is connected to the tip side of the line and to prevent the change from affecting the release operation, relay J which operates due to relay 211 operating is provided to restore the original connections. 115

More particularly, when the calling party is the first to restore the receiver inasmuch as relay J is held up from ground on the sleeve wire 124, no circuit is closed through the right winding of relay 210, for connecting battery to the tip side of the line and the coin ground, does not prevent the release by holding up relay 210. Relay 210 therefore releases, opening the circuit of the usual slow relay 240. The release of 120 125 130

the slow relay energizes the release magnet 214 which releases the connector and the release of the slow relay removes ground from the sleeve conductor 235, which releases the selectors. The selectors release before the coin collecting operations are completed and inasmuch as the ground on the release wire 125, to which relay J is locked, cannot be removed until these operations are completed the circuit referred to from the ground in the coin box to the right winding of relay 210 is not closed.

When the called party restores first, relay 211 releases and reverses the current flow in the calling line. In this event relays J and K cooperate to prevent this condition from affecting release. When the relay J operated upon the response of the called party, it caused relay P to restore and closed a circuit for relay K by attracting its armature 183 this circuit including the grounded sleeve wire 125. Relay K at its right armature in operating prepares a circuit to shunt relay J. When the called party replaces his receiver and reverses the current flow in the calling line, relay P operates and shunts out relay J over resistance 184, conductor 185, armature and front contact of relay K, contact of relay P, conductors 192, 157, 146, 147, inner right armature of relay H H to grounded conductor 148. Relay J releases before relay K closes its back contact, thus preventing relay J from again operating. Relay J restores the original connections to the tip and ring conductors so that the ground in the coin box is now connected to the tip side 164 of the line to which the grounded side of relay 210 is connected. Thus when the calling party restores his receiver, no circuit could be maintained closed from the coin ground to the winding of relay 210 to which the free pole of battery is connected. Thus release is not prevented.

Relay P is located in the tip side of the line rather than the ring side so that if the called party hangs up immediately after the calling party and releases relay 211 thus reversing battery to the calling party before the slow relay in the connector has time to release and remove the ground from the sleeve wire which is holding up relay S, relay P will be operated when relay 211 releases over a circuit from the free pole of battery through right winding of relay 210 to the coin ground, thus short circuiting relay J as described, which reconnects the coin ground to the grounded side of relay 210 and reconnects the side of relay 210 connected to the free pole of battery to the ring side of the line which is open at the switchhook. Thus release is not interfered with.

The operation involved in setting up connections without the aid of the operator

having been described, a connection involving an operator will now be considered. A certain level or levels of selector S contain trunks leading to an operator's position P. The subscriber at station A leases the selectors. The selectors release before the coin collecting operations are completed and inasmuch as the ground on the release wire 125, to which relay J is locked, cannot be removed until these operations are completed the circuit referred to from the ground in the coin box to the right winding of relay 210 is not closed. (Fig. 3) in the well-known manner.

When this trunk is selected a loop including the armature and front contact of the impulse relay R' (Fig. 1) is presented across the tip and ring of the trunk T and relay 300 operates, closing the circuit for operating slow to release relay 301, which at its armature 325 places ground upon the release trunk 346 and terminal 362 through the winding of the tone transformer 302 to hold the preceding switches set in the well-known manner. Relay 300 at its armature 328 also closes a circuit from battery through relay 303 onto the ring side 90 of the trunk which terminates in the manual office, thus completing the circuit for operating the loop relay 347 at said office which causes a lamp 348 to light before the operator, as a signal to her that the trunk has been selected. The return for this circuit is over the tip conductor 342 to ground through the right winding of relay 303 and secondary of coil 302. Relay 303 is marginal and will not operate in series with relay 347. Relay 301 at its armature 326 closes the interrupted generator 306 onto the ring side of the incoming trunk by way of armature 329 of relay 307 which serves to return a ringing tone to the calling subscriber. When the operator inserts plug 400 into jack 314 marginal relay 303 operates due to low resistance relay 403 being substituted for relay 347. Relays 401 and 349 operate also, the former preparing the lamp circuit and the latter cutting off loop relay 347. Relay 303 at its armature 321 closes the circuit for operating relay 307, which locks to the grounded release trunk 346 at armature 331. Relay 307 at said armature removes the short circuit from around the low winding of the tone transformer 302. This short circuit was for the purpose of preventing the class of service tone from being returned to the calling subscriber at the same time as the ringing tone. Relay 307 at armature 329 removes the ringing tone from the trunk and prepares the circuit for relay 308 at armature 330. Relay 307 will remain operated until the trunk has been released. The calling subscriber's class tone coil CT at the line switch by its primary 195 causes tone to be impressed upon the release trunk through its secondary 197 if such line is restricted in the class of calls it 130

makes as shown and described in British Patent No. 15,133 of 1911. This tone is repeated by the tone transformer 302 to the tip side of the trunk T, and the operator in throwing her listening key 422 will detect this tone, which serves to indicate to her the class of service to which the calling subscriber is entitled. In order to remove this tone the operator depresses a tone removal key in the cord (not shown) which causes a momentary interruption of the trunk loop circuit, and relay 303 will momentarily restore. Relay 309, which was operated by relay 303, is a slow releasing relay and will not restore in the interval that relay 303 is released. Relay 303 in releasing its armature 321 closes a circuit for operating relay 310 from ground at armature 331. Relay 310 operates and locks to ground at armature 323 and front contact of relay 309. Relay 310 short circuits the secondary winding of the tone transformer, which causes the tone to be removed from the trunk T. Relay 310 also extends the tip and ring of the subscriber's transmission circuit to the tip and ring of the trunk into which the operator has her plug 400. If the operator, after having removed the tone desires to cause it to be replaced for the purpose of checking, she removes the plug of her cord from the jack for an interval long enough for relays 303 and 309 both to restore. Upon reinserting the plug, relay 303 will operate, closing the circuit for again operating relay 309, but before relay 309 can close its front contact, to which relay 310 was locked, relay 310 will restore, and therefore cause the tone to be replaced on the trunk which tone can again be removed as previously described.

Referring now to Fig. 4. When the operator who we will assume is a toll operator, has built up the connection over plug 405, jack 406 and the intervening trunks to the called line 407, has found the line idle, has applied ringing current, and the called subscriber at station 407 has responded she requests the calling party to deposit the required coins in the coin box. The coins, in dropping in the coin box, strike bells which, in the well known manner, inform the operator of the character of the deposited coins. The operator then picks up a plug P-10 at her position and inserts it in a collect jack J-10 and by means of the dial D-10 and an automatic switch shown in Fig. 4 selects the trunk T shown in Fig. 3 which is multiplied to this automatic switch at 1020, 1021. If the plug is inserted into the collect jack a relay H-10 operates to prepare a circuit from a source of current of 110 volts positive polarity to the selected line to operate the polarized magnet in the coin box to collect the coins. If, on the other hand, the plug P-10 is inserted in the refund jack

R-10, relay H-10 is not operated and consequently negative current of 110 volts is impressed upon the called line to operate the polarized magnet in the coin box in the opposite direction to refund the coins. The upper armature 1023 of the relay H-10 in its attracted position closes a circuit from a tone source 1022 of one character to the operator's head set which informs her that positive impulses of current are being transmitted to the called line. This armature in its retracted position gives a different tone to the operator's head set from tone source 1027 to indicate to her that negative impulses are being transmitted to the called line. The operator is thus informed whether the coin collect circuits are functioning properly or not. As shown in the said Forsberg patent, when the polarized relay operates in either direction it disconnects itself from ground, whereupon the relay H-10 in the coin current circuit ceases to operate to transmit this tone thus informing the operator that the polarized magnet has functioned. She thereupon withdraws the plug P-10 from the jack whereupon the automatic switch of Fig. 4 is restored to its normal position.

More in detail, after the subscriber has deposited the required coins which are to be collected, the operator at position P picks up her plug P-10 (Fig. 4) and touching the tip of the plug to the tip of the jack J-10 and finding the same idle, she inserts it into said jack. The insertion of the plug P-10 closes a circuit for relays E-91 and E-99 over the sleeves of the plug and jack, and relay E-91 thereupon operates the signals 1002 and 1003 at the positions in which the multiples of this jack appear. Relay E-99 in operating disconnects the busy test circuit and connects the dial D-10 to the tip of the plug. Battery on the sleeve of the plug causes the multiples of the seized trunk to test busy at the other positions. The operator knowing the number of the trunk T shown in Fig. 3 because of the designation on the jacks themselves or the designation strips associated with the jacks now rotates her dial to set the automatic switch shown in Fig. 4 to connect with the multiples 1020, 1021 of the used trunk T which appear in this switch. The automatic switch of Fig. 4 and all apparatus shown at the right of the dotted line are located at the automatic office, that is to say in the same office with the selector of Fig. 2. The equipment shown at the left of the dotted line of Fig. 4 is located at the office where jack 314 is located, that is at the manual office. The insertion of the plug P-10 energizes the impulse relay A-10 over the following circuit: free pole of battery, resistance 1050, impulse springs of the dial, armature and front contact of relay 130

E-99 tip of the plug P-10, tip of the jack J-10, conductor 1005, conductor 1006, upper normally closed contact of off normal switch 1007, conductor 1008, impulse relay

5 A-10, conductor 1009, conductor 1010, ring of the jack J-10, ring of the plug P-10 to ground. The impulse relay in operating energizes the usual slow to release relay B-10. Relay B-10 in attracting its outer

10 right armature closes a circuit for the upper winding of relay H-10. This winding of relay H-10 when energized is not sufficiently strong to cause the relay to operate but is sufficient to cause relay H-10 to

15 operate when the current through the lower winding is in the right direction to aid the current in the upper winding; lower winding of relay H-10 will not cause the operation of the relay H-10, when the current flowing the upper winding opposes that flowing in the lower winding. The lower winding however is shunted while the switch

20 shaft is in its normal position.

Upon the return movement of the dial 25 the impulses are transmitted to the impulse relay A-10. Upon each retraction of the armature of this relay an impulse is transmitted over the following circuit to the vertical magnet 1013 of the switch; ground, 30 armature and back contact of relay A-10, inner armature front contact of relay B-10, lower normally closed contact of off normal switch 1007, slow relay C-10, vertical magnet 1013 to free pole of battery. The first

35 step of the switch operates the off normal switch 1007 which removes the short circuit from around the lower winding of the relay H-10, whereupon relay H-10 operates and shifts the armature 1012 from its normal connection with the refund source of 40 110 volts negative current to connection with the collect source of 110 volts positive current.

Upon the first vertical step the off normal 45 switch 1007 operates and the succeeding impulses then pass by way of contact 1015 and the armature and front contact of slow relay C-10. Upon the cessation of the impulses the slow relay C-10 releases preparing a circuit for the rotary magnet 1016 closed upon the return of the dial for the units impulses. The impulses now pass from the back contact of the stepping relay

50 A-10, inner armature and front contact of relay B-10, contact 1015, armature and back of relay C-10, slow relay E-10, outer right hand armature and back contact of relay D-10, rotary magnet 1016 to free pole of battery. Relay E-10 in attracting

55 its outer left armature energizes relay D-10 which in attracting its left armature locks up to the outer right armature of relay B-10. Relay E-10 in attracting its inner left armature operates relay F-10. Relay

60 F-10 in attracting its right armature con-

nects the rotary magnet in the stepping circuit independently of the outer right armature of the relay D-10. Now when the units impulses have all been transmitted the slow relay E-10, after a slight interval, 70

releases. The retraction of its inner left armature opens the circuit through the left winding of relay F-10. If at this time the interrupter 1017 is on a metallic segment

75 relay F-10 will be held up by its armature. When the interrupter passes to the next insulating segment relay F-10 releases and its armature connects relay G-10 over the inner right armature and front contact of

80 relay D-10 to the interrupting machine 80 1017. It will be apparent that the relay F-10 is provided to insure that the first impulse to relay G-10 will be a full one. The brushes 1018 and 1019, being now in

85 contact with multiples 1020 and 1021 of the trunk T shown in Fig. 3, upon the first engagement of the interrupting machine brush with the metallic segment after relay F-10 has released, an impulse is transmitted to

90 the relay G-10, which in attracting its armature connects the source of collect current by way of the brush 1018, multiple 1020, conductor 341, Fig. 3, relay 311 and to ground.

95 Relay 311 in turn operates relay 312. Relay 312 in operating reverses the battery toward the calling subscriber, which serves to cause the pay station repeater Fig. 1 to

100 prepare to control the disposition of the coin as described in detail. At the end of the period, relay 311 restores, but relay 312 is slow to release and before it can restore, relay 313 is operated and locks to the release trunk. The next period of coin control current causes relay 311 to operate and the coin control current passes toward the calling subscriber by way of front contacts of relays

105 313 and 312, this circuit including switch hook springs of the substation telephone set, contact 120 in the coin box, polarized magnet PR of the coin box to ground. Current will flow through relay J'-10 (Fig. 4) to

110 ground at the coin box each time relay G-10 operates until the coins have been collected in case they are not collected upon the first operation of the polarized magnet PR. When the polarized magnet PR operates and collects the coins the contact 120 in

115 the coin box at the substation is opened and consequently relay J'-10 no longer operates. Each time relay J'-10 operates tone is placed on the toll switching trunk to indicate to the operator that the proper current is being sent out to the line. This circuit leads from a source 1022 over the front

120 contact and armature 1023 of the relay H-10, armature and front contact of relay J'-10, condenser 1069, brush 1019, multiple 1021, conductor 340 Figs. 4 and 3, which

125 multiple is connected to the ring conductor

130 65 E-10 in attracting its right armature con-

of the trunk from whence it is transmitted to the operator's head set. The operator, ceasing to hear the tone knows that the coins have been collected and pulls out the plug

- 5 P—10. If the polarized magnet fails to collect the coins or if the coin box fails to function properly for some reason or other the contact 120 remains closed and the repeated impulses of tone will inform the operator of 10 this condition and she will pull out the plug and report the line. The removal of the plug causes the release of the impulse relay A—10 and slow relay B—10 which closes the following circuit for the release magnet 15 J—1025; free pole of battery, magnet J—1025, upper contact of the off normal switch 1007, inner armature and back contact of slow relay B—10 armature and back contact of relay A—10 to ground. The release magnet restores the switch and the switch, upon reaching its normal position, restores off normal switch, 1007.

If the operator had plugged into the refund jack R—10, if for any reason the coins 25 were to be refunded, the current in the lower winding of relay H—10 would oppose that flowing in the upper winding and relay H—10 would not operate when off normal switch 1007 opened the shunt about the lower winding. Consequently the armatures 30 of relay H—10 would have remained retracted, the armature 1012 connecting the refund source of negative current to the called line to operate the polarized magnet 35 PR in the opposite direction to refund the coins to the subscriber. Armature 1023 at its contact would connect a source of refund tone 1027 in circuit with the operator's head set each time the relay J'—10 operated. As 40 in the case where the coins were collected, the toll operator ceasing to hear refund tone impulses knows that the coins have passed through the box and she removes the plug from the refund jack. It is of course understood that the tone sources 1022 and 1027 are of different character for example, the refund source can be 460 pulsations per second and the collect source 150 pulsations per second.

- 45 50 When the calling party hangs up his receiver, relay 300 will restore and will transfer the ring of the trunk from battery through the low resistance winding of 303 to battery through the high resistance 339 and high resistance relay 308. The replacing of the low resistance battery feed with the high resistance battery feed causes supervisory relay 403 in the cord circuit to release to light lamp 402 to signal the operator that the calling party has hung up his receiver, whereupon she removes the plug 400 from jack 314 which releases relay 308. This relay in retracting its armature opens the circuit of relay 309 which in turn releases slow relay 301. This relay in retracting its ar-

mature 325 removes the holding ground from the release trunk which causes the restoration of the automatic switch as described.

If a refund is to be made for the call the 70 operator will not actuate her dial D—10 to select the trunk T but merely withdraws the plug 400 from jack 314 and assuming the calling party had replaced his receiver, the coin collect circuit of Fig. 1 would then 75 function to refund the coins automatically exactly as described in detail in the case where the calling party replaced his receiver after failing to obtain a response from the 80 called party.

85 From the foregoing it is apparent that by virtue of this invention the operator is relieved of considerable work in refunding coins, such work being performed automatically by the central office equipment.

What is claimed is:

1. In a telephone system, telephone lines, check controlled devices associated therewith, an operator's position, automatic switches and trunks for extending connections from said lines to said position, means controlled from said position for rendering an established connection metallically continuous between a calling line and said operator's position, means controlled by said operator for governing the operation of said device of the calling line over said connection, and means for automatically operating said device in case the operator fails to do so.

2. In a telephone system, telephone lines, coin boxes associated therewith, an operator's position, automatic switches and trunks for extending connections from said lines to said position, means controlled from said position for rendering an established connection metallically continuous between a calling line and said operator's position, means controlled by the operator for operating the magnet of a calling line coin box over said connection to collect or refund a deposited coin, and means for automatically operating said magnet to refund the deposited coin in case the operator fails to do so.

3. In a telephone system, telephone lines, check controlled devices associated therewith, a repeater circuit, an operator's position, automatic switches and trunks for extending connections from said lines through said repeater circuit to said position, a relay in said repeater circuit controlled from said position for rendering an established connection metallically continuous between a calling line and said operator's position, means controlled by said operator for governing the operation of said device of the calling line over said connection, and means for automatically operating said device in case the operator fails to do so.

4. In a telephone system, telephone lines, check controlled devices associated therewith, an operator's position, automatic switches and trunks for extending connections from said line to said position, means controlled from said position for rendering an established connection metallically continuous between a calling line and said operator's position, a plug and jacks at said operator's position for governing the operation of the devices of said calling line over said metallic connection, and means for automatically operating the device in case the operator fails to do so.
5. In a telephone system, telephone lines, coin boxes associated therewith, an operator's position, automatic switches and trunks for extending connections from said lines to said position, means controlled from said position for rendering an established connection metallically continuous between a calling line and said operator's position, means controlled from said operator's position for operating the magnet of the coin box of a calling line to collect or refund a deposited coin over said connection, and means for automatically operating said coin box magnet during the taking down of said connection in case the operator fails to do so.
6. In a telephone system, telephone lines, coin boxes associated therewith, an operator's position, automatic switches and talking trunks for extending calling lines to said position, automatic switching means and special coin control trunks controlled from said position for selecting the talking trunk taken for use by a calling line, sources of current for operating the magnets of said coin boxes, means at said position for impressing current on the calling line via said special trunks to selectively operate said coin box magnet of the calling line, and means for automatically applying current to the calling line to operate said coin box magnet in case the operator fails to do so.
7. In a telephone system, telephone lines, coin boxes associated therewith, an operator's position, automatic switches and
- talking trunks for extending calling lines to said position, automatic switching means and special coin control trunks controlled from said position for selecting the trunk taken for use by a calling line, sources of current for operating the magnets of said coin boxes, means at said position for impressing current on said line via said special trunks to selectively operate the coin box magnet of the said line, and means for automatically applying current to the said line during the breaking down of the connection to operate the coin box in case the operator fails to do so.
8. In a telephone system, telephone lines, coin boxes associated therewith, an operator's position, automatic switches and trunks for extending calling lines to said position, automatic switches controllable from said position and containing multiples of said trunks, sources of collect and refund current, means at said position for impressing current from either source on one of said calling lines via one of said last mentioned automatic switches, and means for automatically applying current to said calling line during the breaking down of the connection to operate its coin box magnet in case the operator fails to do so.
9. In a telephone system, telephone lines, coin boxes associated therewith, an operator's position, automatic switches and trunks for extending calling lines to said position, automatic switches controllable from said position and containing multiples of said trunks, sources of collect and refund current, means at said position for impressing current from either source on one of said calling lines via one of said last mentioned automatic switches, and means for automatically applying current to said calling line during the breaking down of the connection to operate the coin box magnet to refund the deposited coin in case the operator fails to do so.

In witness whereof, I hereunto subscribe my name this 30th day of July A. D., 1923.

BERT G. DUNHAM.
